3 Claims. (Cl. 194—9)

1

The present invention relates to prepayment coin-box apparatus for generating coin-released electrical impulses and is particularly suitable for telephone pay stations.

In existing prepayment coin boxes, designed for receiving coins of different denominations and comprising devices for generating coin-released impulses, a separate coin chute is provided for every coin denomination and each chute has an element for detecting the presence of a coin and causing the transmission of a train of impulses corresponding to the value of the inserted coin.

It is an object of my invention to improve such coin-controlled pulse transmitting apparatus by reducing the large number of control elements needed in apparatus of the above-mentioned, conventional design.

To this end, and in accordance with one of the features of my invention, I equip a coin-box apparatus with only one coin chute for all types of coins to be inserted and provide this chute with a single coin feeler element which is actuated by an inserted coin and in turn actuates a pulse generator, the extent of the coin feeler movement determining the number of pulses to be transmitted by the generator.

These and more specific objects and features of my invention will be apparent from the following description of the embodiment illustrated on the drawing in which:

Fig. 1 is an elevation of a prepayment coin box apparatus;

Fig. 2 is a plan view and Fig. 3 a front view of the same apparatus;

Fig. 4 shows a cam device pertaining to the same apparatus; and

Fig. 5 is an example of a wiring diagram of a telephone pay station equipped with such an apparatus.

Similar parts in Figs. 1 to 4 are denoted by the same respective reference characters. The reference characters added in parenthesis in Figs. 1 to 3 refer to the correspondingly denoted elements in Fig. 5; and the parenthetical reference characters added in Fig. 5 refer to the correspondingly denoted elements in Figs. 1 to 3.

The coin-box apparatus according to Figs. 1 to 4 is designed for the reception of coins of four different denominations, for which the following Swiss coin values have been chosen: 10 centimes, 20 centimes, 50 centimes and 1 franc.

The impulse unit is 10 centimes. The number of impulses to be issued for the other respective coins is always an integral multiple of the unit;

2

that is, ten pulses are to be issued after the insertion of a one-franc piece.

The apparatus has a single coin chute 1 composed of two plates 2 and 3 spaced by intermediate pieces 4 and 5. A coin 6 (20 centimes) is shown as about to enter the coin chute, having been passed by the coin tester. Shown at 6a, in broken lines, are four coins of the respectively different denominations to indicate the respective positions that these coins will reach at the bottom of the coin chute, only one coin, of course, being in that position at a time. In this position, the coin tilts the feeler arm 7a of a pulse control lever 7 an extent determined by the coin size. This tilting movement causes a lug 8 of lever 7 to shift along a milled slot 11 extending in the direction of a cam shaft 10 carrying four cams 9a—9d (Figs. 3, 4). The extent of this shifting movement is determined by the proportion of the arms 7a and 7b of lever 7. Since the coin inserted is a 20-centime piece, the lug 8 is displaced to the cam 9b. With the movement of control lever 7 about its pivot 31, a mercury switch 13 attached thereto is lowered and closes an energizing circuit for a motor 14.

The replacement of the spring contacts hitherto used for this purpose in prepayment coin boxes by a see-saw mounted mercury switch constitutes a particular advantage since the forces exerted upon a pulse-control lever or similar coin feeler element by the weight of the coin are naturally of a very small order. In order to avoid interference with the movement of the pulse control lever 7 by the rigidity of the electric leads, the current is applied to the mercury switch 13 through contacts 15, 16 whose contact points are arranged on the pivot axis of the lever 7.

The motor 14, when thus energized, drives a pulse wheel 19 and the cams 9a—9d through a worm 17 and a gear 18. By means of the pulse wheel 19 and the contact 20, ten impulses are generated for one full turn of shaft 10. For the following reason, only two of the ten pulses are effective: Just after the shaft 10 has begun its rotary movement, the cam 9b, acting upon lug 8, displaces the lever arm 7b in a direction parallel to the axis of its pivot 31. As a result, the lever arm 7b opens a short-circuit contact 22 with which the arm 7b is connected by a link 33 (Fig. 3). The contact 22 is electrically parallel connected with the pulse contact 20. After the issuance of two impulses, contact 22, under control by the revolving cam 9b, again closes, so that the remaining eight pulse movements of con-

tact 20 remain ineffective. While thus only two pulses are transmitted in response to the insertion of a 20-centime piece, it will be understood that the four cams 9a to 9d are differently shaped so that, for instance, only one pulse is issued for a 10-centime piece and all ten pulses for a one-franc piece.

When the telephone receiver is lifted from its rest, i. e. before the coins are inserted, the electromagnet 23 (Figs. 1, 2) is energized. Apart from actuating four contacts 24a to 24d, this magnet moves a coin switch member 21 clockwise about its pivot 30 (Fig. 2). A slide 26 connected with the coin switch member 21 is thus moved to close the lower end of the coin chute 1, so that the coin inserted is held in the operative range of the impulse lever. The electromagnet 23 is deenergized at a moment prior to the pulse generation. The coin then drops from position 6a through position 6c (Fig. 1) into a cash box (not shown).

Two slides 27, 28 and a stop or stud 29 are connected with the coin switch member 21. The slide 27 serves to close the upper part of the coin chute when the electromagnet 23 is deenergized, while the slide 28 then opens one of the narrow sides of the coin chute. Consequently, any coins inserted into the apparatus while pulses are being transmitted will drop out, as shown at 6b, into the return chute. The user may again insert this coin after termination of the pulse transmission period. It is, of course, also possible to close the coin slot or slots by the electromagnet 23 when the electromagnet is energized, so that no coins can be inserted during this period.

If a user inserts two coins in quick succession, it may happen that both coins enter the coin chute before the electromagnet 23 is again deenergized. The stud 29 then prevents the second coin from falling into the cash box without having caused a pulse transmission. When the first coin is being released, the stud 29 retains the second, upper coin until the magnet 23 is again energized.

The performance and advantages of the coin-controlled pulse transmitting apparatus described in the foregoing will be more fully understood from the example of an application for a telephone pay station given in the following in conjunction with the circuit diagram of Fig. 5.

Before describing other details of the circuit diagram a few explanatory remarks appear proper. As apparent from the foregoing, the motor 14 for actuating the pulse issuing device of the above-described apparatus may consist of any suitable start-stop drive which in response to a signal causes the pulse wheel 19 and the control cams 9a through 9d to perform one full revolution. For telephone purposes, however, I prefer using a start-stop motor of the stepping-switch type known, for instance, from the article by M. Langer in the German periodical Elektrotechnik, vol. 2, No. 1, January 1948, page 25. Such a motor has two stator coils M1 and M2 (Fig. 5) perpendicular to each other which act upon a rotor with salient poles. The stator coils are energized and deenergized under control by two interruptor contacts m1 and m2 which are actuated by the operation of the motor. Additional contacts v3 and mk2 are provided for rapidly arresting the rotor. When contacts v3 and mk2 are closed, the two stator coils M1 and M2 are simultaneously energized to lock the rotor. The contact v3 pertains to a locking magnet V which is identical with the magnet denoted

by 23 in Figs. 1 and 2. The contacts mk1, mk2 and m1 are controlled by respective cams driven by the stop motor. The contacts mk1 and mk2 are closed when the drive motor is at rest and are open during the revolution of the pulse issuing device. The pulse contact m1 (Fig. 5) corresponds to the pulse contact 20 shown in Fig. 1 and, as explained, is opened ten times during one complete revolution of the pulse contact wheel driven by the start-stop motor.

In other respects, the telephone substation according to Fig. 5 is largely similar to conventional designs, having a telephone receiver B, a microphone D, a bell E, a transformer U, hook switch contacts H1, H2, H3, a dial switch (not shown) with a pulse contact i and an off-zero contact k, and several other components to be referred to in a later place.

The substation is connected with the exchange by two wires a and b. The exchange equipment, located at the right hand side of the vertical dot-and-dash line entered in Fig. 5, may have any conventional design and for the purposes of the invention is equipped with a group of relays located ahead of the pre-selector or line finder stage (not illustrated). This relay group comprises three relays C, A, and X. Relay C has a contact c1 and is energized when a suitable cash relay set is selected automatically or by the operator. The contact c1 for any selected relay set is then closed. The relay A serves to receive the dial pulses. It has two coils denoted by I and II respectively and responds to loop current flowing through wires a and b. The contact means of relay A, which may be designed and operative in any conventional manner, are not illustrated. The relay X serves for responding to the pulses received from the coin-controlled pulse transmitting apparatus. Relay X is of the differential type and has two coils I, II so connected that the relay may respond either through only one of its coils (II) when pulses are received passing from wire a to ground, or it may respond with both coils I and II when the coils are energized in the cumulative sense. Relay X, however, does not respond to loop current because the fluxes of its two coils I and II then cancel each other.

For establishing a connection, the telephone receiver B at the pay station is first lifted so that the contacts H1 to H3 are actuated. Ground potential is then applied to the b wire through the contacts s1, H1, v1 and the rectifier G1. As a result, the line finder stage (not shown) is actuated in the exchange. A cash relay group, such as the group C, A, X shown in Fig. 5 is then switched in. The minus potential of the current source in the exchange, here schematically shown by the symbol of a battery is then connected with wire a through coil II of relay A and coil II of relay X. This establishes the following circuit: ground, battery, coil II of relay A, coil II of relay X, contact c1, wire a, rectifier G3, contacts m1 and m2, transformer U, coils I and II of magnet V, contacts i, H2 and mk1, rectifier G2, contact v1, rectifier G1, contacts H1 and s1, ground. The magnet V (i. e. magnet 23 of the apparatus shown in Figs. 1 and 2) becomes energized in the just mentioned circuit. The pickup delay of the differential relay X in the exchange is such that the contact x1 in the exchange remains for some time in the illustrated position. Magnet V (23 in Figs. 1 and 2) now opens the coin chute by withdrawing the slide member 27, (Fig. 1) and actuates the contacts v1 through v4 (Fig. 5, corresponding

to contacts 24a through 24d in Fig. 2). The contact v_1 , now open, is latched in this position by the hook switch until the hook switch, at the termination of the telephone connection, is returned to its rest position. Hence, during the further operation, the contact v_1 is open regardless whether or not the magnet V (23) performs additional switching movements. Consequently, now the circuit extends through wire b, coil I of relay X, contact x_1 , coil I of the now responding relay A and ground, instead of through contact v_1 , rectifier G4, contacts H1 and s_1 , ground. A coin inserted into the coin chute of the pulse transmitting apparatus now causes the mercury switch Q (corresponding to switch 13 in Figs. 1, 2) to close. This completes the following circuit: ground switch Q, contacts H2 and i , magnet V, transformer U, contacts m_1 and m_{1k} , rectifier G3, wire a, contact c_1 , coil II of relay X, coil II of relay A, battery, ground. The differential relay 20 X is asymmetrically energized in this circuit and therefore closes its contact x_1 . Thereafter the magnetic fluxes of coils I and II in relay X act cumulatively thus retaining the contact x_1 in the actuated position. Relay A remains energized by means of its winding II.

The above mentioned stator coil M1 of the start-stop motor now receives energizing current in the circuit: ground, switch Q, contacts m_1 and m_1 , stator coil M1, wire b, coil I of relay X, contact x_1 , resistor W, battery, ground. The motor now performs a stepwise operation by alternately actuating its interruptor contacts m_1 and m_2 which alternately reduce and increase the current in the two stator coils.

The rectifier G2 prevents an excitation of the motor by currents of the opposite direction. As explained above, the coin controlled pulses are now produced by means of the contact m_1 (20), and the number of pulses corresponding to the 40 denomination of the inserted coin is made effective by the opening of the parallel contact m_{1k} (22). The opening of contact m_{1k} causes energization of the relay S, whereby the coin-controlled pulses are caused to energize the differential relay X in the exchange in the following circuit: ground, contact s_1 (or Q) and s_2 , pulse contact m_1 , valve G3, wire a, contact c_1 , coil II of relay X, coil II of relay A, battery, ground. The excitation of relay X has the further consequence that the magnet V is shorted by the contact s_2 so that the coin switch member 21 (Figs. 1, 2) is shifted as described previously.

After one complete revolution of the pulse wheel (19 in Fig. 1), the start-stop motor of the pulse transmitting device is again arrested by the simultaneous excitation of its two stator coils M1 and M2 (Fig. 5) through the two then closed contacts m_2 and v_3 . Due to the short-circuit through contact m_2 , relay S can no longer hold its armature and becomes deenergized after the elapse of a time delay period. The drop-out delay of relay S is sufficient for the motor to come to standstill. The opening of the short-circuit of magnet V at contact s_2 causes a new shifting of the coin switch member. The differential relay X also returns to its rest position due to the opening of contact s_1 .

The pulse transmitting apparatus is now ready for the insertion of another coin. After insertion 70 of the full amount to be paid, the user may start dialing the number of the subscriber with whom a connection is desired. This occurs in the conventional manner, the dial switch causing the pulse contact i to open and close repeatedly while

the off-zero contact k remains closed during the dialing operation. After termination of the connection, i. e. when the receiver is placed back on its holder or hook, all hook switch contacts are 5 reset to the illustrated positions and the locking magnet V (23 in Fig. 1, and 2) becomes demagnetized.

For actuating the cashing magnet KM, a positive direct voltage with a grounded minus pole is placed on wire a in the exchange for a short interval of time. This establishes the circuit: positive D.-C. voltage, wire a, valve G4, magnet KM, rectifier G5, contact v_2 , ground. If no connection has been established with the called subscriber, the inserted coins are returned by placing a positive direct current voltage with a grounded minus pole on the wire b of the connecting line. This energizes the return magnet RM causing the coins to drop into a return chute.

It will be obvious to those skilled in the art upon a study of this disclosure, that my invention permits of various modifications especially as regards design details of the pulse transmitting apparatus. For instance, instead of providing a polarity of individual control cams 9a through 9d, a single disk or cam structure with several machined cam curves may be provided. It may also be advantageous to design the coin feeler structure as a linearly displaceable slider instead of a lever, the extension of displacement being controlled by the size of the inserted coins substantially in the same manner as described above.

I claim:

1. Coin-controlled purse transmitting apparatus, comprising a single coin chute for the coins of all denominations to be inserted, a coin feeler structure projecting into said coin chute and being engageable with the periphery of the respective inserted coins, said feeler structure being displaceable by the coins respective different amounts depending upon the coin size, a pulse issuing device having drive means responsive to coin insertion and having pulse contact means connected with said drive means to operate a given number of times for each individual operation of said drive means, said device having pulse control means for controlling said contact means to issue during each said operation respectively different numbers of pulses dependent upon the denominations of the respective inserted coins, said control means comprising a plurality of different control cams connected with said drive means to be driven thereby, and said feeler structure being selectively engageable with said control cams depending upon the amount of displacement of said feeler structure.

2. Coin-controlled pulse transmitting apparatus, comprising a single coin chute for the coins of all denominations to be inserted, a coin feeler structure projecting into said coin chute and being engageable with the periphery of the respective inserted coins, said feeler structure being displaceable by the coins respective different amounts depending upon the coin size, a pulse issuing device having pulse contact means and a pulse wheel and drive means responsive to coin insertion, said drive means being connected with said wheel for revolving it once for each operation and said wheel being engageable with said contact means for actuating it a given number of times during said operation, said device having pulse control means for controlling said contact means to issue during each said operation respectively different numbers of pulses dependent upon the denominations of the respective inserted

coins, said control means comprising a plurality of different control means coaxially joined with said pulse wheel to revolve together therewith, and said feeler structure having a path of coin-controlled displacement extending along said cams and being selectively engageable with said respective cams depending upon the amount of said displacement, whereby the selected cam controls the number of issued pulses in accordance with the denomination of the coin inserted at a time.

3. In coin-controlled pulse transmitting apparatus according to claim 1, said feeler structure comprising a lever member having a pivot axis and being tiltable about said axis in the direction of said coin-controlled displacement, said lever member being also movable by said respective cams in a direction parallel to said axis, and electric switch means mechanically connected

with said lever member and responsive to the cam-controlled movement, said switch means being electrically connected with said pulse contact means to render it ineffective during a portion of said operation dependent upon the cam selectively engaged by said lever member.

OTTO MOSER.
